SHADE BRACKET

Edward Jonas, New York, N. Y., assignor to
Universal Home Specialties, Inc., Philadelphia,
Pa., a corporation of Delaware

Application August 13, 1932. Serial No. 628,655

7 Claims. (Cl. 156—24)

This invention relates to shade brackets and more particularly to that type of shade bracket which is adapted to be mounted upon the upper sash of a window to permit the raising and lowering of such upper sash with accompanying movement of the shade for the purpose of allowing ventilation of the upper portion of the room.

Devices of this character have heretofore been suggested, but in every case, they were open to such pronounced disadvantages for one reason or another that they have never gone into extensive use. They entail invariably cutting of the sash or the use of screws, nails or other attaching devices which mar the paint or finish of the sash and require skill and labor.

The object of the present invention is to provide a simple, convenient and economical construction, which will serve as a mounting for one or more shades upon the upper sash, but which will permit the automatic positioning of the shades out of the path of the lower sash when it is desired to move the sashes by one another for cleaning or for any other purpose.

The invention embodies numerous novel features constituting marked improvements on prior structures and directed more particularly to economy and efficiency in operation.

Speaking generally, the shade bracket of the present invention is adapted to be removably mounted upon the upper sash of a window without the employment of nails, screws or any other attaching means and by virtue rather of the inherent properties and construction of an attaching clip adapted to straddle the upper edge of the upper sash and to resiliently mount the bracket thereon. This resilient clip is provided with bearings positioned at some little distance from the upper edge of the sash and in these bearings are journalled trunnions of a supporting arm which is preferably of angular form, and this arm is provided with means to support one or more shades as may be desired. The arm is so formed that when the sashes are moved by one another, the arm will engage with the lower sash at a point considerably removed from the pivot of said arm, so that as the sashes pass one another, the arm will be automatically moved into a position to shift the shades over the upper edge of the upper sash through the employment of a camming action hereinafter described in detail.

The arrangement is such that the sashes will not exert a pressure upon the pivots on dead centers which would serve to unduly strain the structure or cause the bracket to be disengaged from the sash.

Features of the invention other than those adverted to, will be apparent from the hereinafter detailed description and claims, when read in conjunction with the accompanying drawing.

The accompanying drawing illustrates different practical embodiments of the invention, but the constructions therein shown are to be understood as illustrative, only, and not as defining the limits of the invention.

Figure 1 is a perspective view of a bracket embodying the present invention, the same being associated with upper and lower sashes of a window which are shown in fragmental perspective section in this figure.

Figure 2 is a fragmental section on the line 2—2 of Figure 1.

Figure 3 is a similar view of a modified form of the invention associated with an upper sash.

Figure 4 is a detail of a modified form of construction.

Referring to the drawing, and more particularly to Figures 1 and 2, 1 designates the upper sash and 2 the lower sash of a window assembly. The present invention as shown in this figure embodies an attaching clip 3, constructed from sheet metal and preferably from thin spring steel although any other appropriate material possessing the necessary resiliency and strength may be utilized in the construction of this element.

The spring clip 3 is of inverted U-shape cross section and of a size adapting it to straddle the upper edge of the upper sash 1. One leg of the clip 3 is flared outwardly at its end, as indicated at 4, so as to facilitate its placement on the sash, while the other leg is bifurcated or cut off as indicated at 5 to provide depending strips 6, which, when blanked out, are provided at the lower ends of their contiguous edges with perforated ears 7 bent at right angles to the strip 6 and adapted to form bearings for the pivoted arm of the bracket. This arm is designated generally by the reference character 8.

The arm 8 is provided at its upper end with laterally extending alined trunnions 9 and from these trunnions, the arm extends downwardly to form an upright portion 10, at the base of which the arm is bent at substantially right angles and given a quarter twist indicated at 11 to form a horizontal part 12. The trunnions 9 are formed on the arm by cutting notches 19 in the opposite lateral edges of the arm to produce the projecting trunnions, which, after being passed through the bearings 7 may be riveted or headed as shown at 22 at the left side of Figure 2. For the sake of clearance the right hand trunnion in

Figure 2 is shown prior to the heading operation, but both trunnions are headed when the parts are fully assembled. With this arrangement, the material employed is economized and 5 nevertheless the upstanding portion of the arm is adapted to enter the cut out 5 of the spring clip when the arm is in elevated position herein-after described.

In the outer end of the horizontal part 12 is 10 an aperture 13 shaped to receive and hold the trunnion of a shade roller and from one side of this aperture extends a slot 14 which facilitates the passage of the trunnion into the aperture 13, the trunnion being passed longitudinally 15 through the slot 14 into the aperture 13 and then turned to occupy a vertical position within this aperture.

If desired, the arm may be cut off along the line 15 if the single shade is to be supported, but 20 in the structure shown in Figure 1, the arm has a depending portion 16 having therein a second aperture 17 for the trunnion of a second shade roller, and with this aperture 17 is also associated a slot 14 to facilitate the entry of the shade roller 25 trunnion into the slot 17. The angular relation between the slot and the aperture in each instance precludes inadvertent disengagement of the trunnion from the aperture.

In Figure 1, the bracket shown is that adapted 30 to receive the angular trunnion of the shade roller or rollers, but it will be understood that the companion bracket simply has circular apertures for the circular trunnions of the corresponding shade rollers.

Attention is called to the fact that at the elbow 35 of the arm, said arm is bent on the arc of a circle as indicated at 18 forming in effect a cam face, the lowermost point of which is directly above the line 21, shown on the lower sash 2. This line 40 21 is obviously at a considerable horizontal distance from the axis of the trunnions 9 by which said arm is pivoted on the spring clip, and, consequently, when it is desired to pass the sashes by one another, this may be done without thought 45 of the shades mounted on the bracket, for as the upper sash is lowered the cam surfaces 18 of the supporting arms will engage with the lower sash at points appreciably off center of their pivots with the result that the supporting arms will be 50 pivoted upwardly and swung upwardly and outwardly over the upper edge of the upper sash. The cut out 5 of the spring clip allows the up-standing portion 10 of the arm to enter into this cut out and hug closely to the upper sash, as indicated in dotted lines in Fig. 1, whereby 55 the sashes are free to pass one another without obstruction. The camming surfaces 18 thus provide for an automatic shifting of the supporting arms into an out of the way position and 60 there is no tendency to disengage the brackets from the upper sash during this operation.

In Figure 3, I have shown the manner in which the present invention may be manufactured in wire. Here the spring clip 3a, which corresponds 65 to the clip 3, is made by bending the single length of wire into an inverted U-shaped structure and curling the free ends of the wire to form bearings 7a for the trunnions 9a of the arm 8a which trunnions are preferably headed at 22a. A camming surface 18a is also provided and the wire 70 forming the arm is twisted and bent to produce a structure adapted to support two shade rollers as will be well understood. Resilient wire is used for this purpose, but such wire is sufficiently stiff to properly support the weight of 75

the shade. The resiliency of the wire, however, may be utilized in the formation of the slot 14a in such manner as to permit the trunnion of the shade to be sprung into the aperture 13a through a constricted mouth 20 as clearly shown in this figure.

It will be noted that the supporting arm is made of a single length of wire twisted and bent in the novel manner shown to provide a structure of extreme simplicity and marked economy.

In Figure 3, the supporting arm is shown as provided with an integral depending portion 16a in which is formed the aperture 17a for the lower shade roller, but, if desired, this depending portion 16a may be omitted as illustrated in Figure 4 if but a single shade is desired.

It will of course be understood that the spring clip is made of such size and shape as to cooperate with windows of standard sizes and conventional forms, and experience has shown me that the wire or sheet material used in the making of the spring clip may be sufficiently thin to occupy the clearance space normally provided in conventional windows, so that it will be unnecessary to cut or in any manner whatsoever modify the window construction. To attach the bracket of this invention to a conventional window, it is only necessary to lower the upper sash and press the supporting clips of the two brackets thereover.

It will be noted that the weight of the shade and its roller will normally hold the spring clips to a seat at the upper edge of the sash and no force whatsoever is exerted in the direction which would tend to displace the bracket from the sash.

The structure of this invention is unusually simple and economical to manufacture. It is thoroughly efficient in use and absolutely automatic in its operation of moving the shade to a point exterior of the window when sashes are 115 caused to pass by one another. It will of course be understood that after the supporting arms have been moved to a position upwardly and over the top of the sash, they are manually manipulated to return them to their normal positions.

It will be noted that the apertures 13 and 17 have slots 14 associated therewith in a manner which is different from that found in shade brackets in the past. The use of the slot 14 125 permits the trunnion to enter the aperture 13 from the slot. In other words, the round trunnion is inserted into one bracket and the angular trunnion is thereupon swung on an arc of a circle to enter the angular trunnion into the slot 14 130 and said trunnion is caused to traverse the length of the slot and enter the aperture 13 or 17 as the case may be. When this trunnion is turned as hereinbefore stated into its normal position within the aperture, it cannot become released 135 therefrom and even when the bracket is swung up as indicated in dotted lines in Figure 1 there will be no tendency whatever for the shade roller to fall out.

The foregoing detailed description sets forth 140 the invention in its preferred practical forms, but the invention is to be understood as fully commensurate with the appended claims.

Having thus fully described the invention, what I claim as new and desire to secure by Letters 145 Patent is:

1. A shade bracket embodying a spring clip shaped and proportioned to straddle and grip an upper window edge of the upper sash adjacent one lateral edge thereof, one side of said clip 150

- being provided at a point spaced from its upper edge with transversely aligned bearings, a substantially L-shaped supporting arm, one end of which is provided with pivots cooperating with 5 said bearings and the other end of which is provided with an aperture for a shade roller trunnion, said arm being provided at its elbow with a curved camming surface adapted for engagement and cooperation with the upper edge of a 10 cooperating lower window sash to force said supporting arm to swing upwardly when the associated sashes are moved by one another.
2. A shade bracket embodying a spring clip adapted to straddle and grip the upper edge of an 15 upper window sash adjacent one lateral edge thereof, said clip being provided at a point spaced from its upper edge with transversely aligned bearings, a substantially L-shaped supporting arm, one end of which is provided with pivots 20 cooperating with said bearings and the other end of which is provided with an aperture for a shade roller trunnion, said arm being provided at its elbow with a curved camming surface adapted for engagement and cooperation with the upper edge of a 25 cooperating lower window sash to force said supporting arm to swing upwardly when the associated sashes are moved by one another, the free end of said arm being also provided with a 30 depending portion provided therein with an aperture for the trunnion of a second shade roller.
3. A shade bracket embodying a spring clip of resilient sheet metal of inverted substantially U-shaped cross section adapted to straddle and grip the upper edge of an upper window sash with the leg of the clip which will over lie the inner 35 face of the sash bifurcated by a cut out slot and provided at its lower end with spaced apart perforated bearings, a substantially L-shaped supporting arm provided at one end with pivots 40 cooperating with said bearings and positioned to register with the cut out slot of the clip, the other end portion of said arm being twisted through substantially 90 degrees and provided at its free 45 end with an aperture to receive a shade roller trunnion, said arm being formed at its elbow with a curved camming surface adapted to overlie and be engaged by the upper edge of an associated lower window sash when the associated sashes 50 are passed by one another to swing the supporting arm upwardly until that portion of the arm adjacent the pivots enters the cut out slot of the clip for the purpose of moving the shade associated with said bracket upwardly and over the upper edge of the upper sash.
4. A shade bracket embodying a spring clip comprising a length of wire bent into substantially inverted U-shape form to straddle and grip the upper edge of an upper window sash with the free ends of the wire adjacent the inner face of said sash and said free ends being curled to provide bearings, a supporting arm embodying a single length of wire returned upon itself and with said opposite ends bent into parallel relation 60 and extending through said bearings to mount the arm for pivotal movement on the clip, said arm being of substantially L-shaped form with its elbow rounded to form a camming surface adapted to engage with the upper edge of an as- 65 sociated lower window sash and the normal horizontal portion of said arm being twisted and bent into a loop to receive a shade roller trunnion.
5. A shade bracket embodying a spring clip adapted to straddle and grip the upper edge of an upper window sash adjacent one lateral edge thereof, said clip being provided at a point spaced from its upper edge with transversely aligned bearings, a substantially L-shaped supporting arm, one end of which is provided with pivots cooperating with said bearings and the other end of which is provided with an aperture for a shade roller trunnion, and a depending part at the latter end of the arm provided with an additional aperture for the trunnion of a second shade roller, 80 said shade roller apertures being formed with entering slots each extending from one side of its associated aperture and closed at its opposite end to provide for convenient entry of the shade roller trunnion into its aperture and to preclude inadvertent disengagement of the shade trunnion from its aperture, said arm being provided at its elbow with a curved camming surface adapted for engagement and cooperation with the upper edge of an associated lower window sash to force said supporting arm to swing upwardly when the associated sashes are moved by one another.
6. A shade bracket embodying a saddle of inverted substantially U-shaped cross section adapted to straddle an upper edge of the upper 105 window sash with the leg of the saddle which will over lie the inner face of the sash bifurcated by a cut out slot and provided at its lower end with spaced apart perforated bearings, a substantially L-shaped supporting arm provided at one end 110 with pivots cooperating with said bearings and positioned to register with the cut out slot of the saddle, the other end portion of said arm being twisted through substantially 90 degrees and provided at its free end with an aperture to receive 115 a shade roller trunnion, said arm being formed at its elbow with a curved camming surface adapted to overlie and be engaged by the upper edge of an associated lower window sash when the sashes are passed by one another to swing the supporting arm upwardly until that portion of the arm adjacent the pivots enters the cut out slots of the saddle for the purpose of moving the shade associated with said bracket upwardly and over the upper edge of the associated upper sash.
7. A shade bracket embodying a saddle of inverted substantially U-shaped cross section adapted to straddle the upper edge of an upper window sash adjacent one lateral edge thereof, 120 said saddle being provided at a point spaced from its upper edge with transversely aligned bearings, a substantially L-shaped supporting arm, one end of which is provided with pivots cooperating with said bearings and the other end of which is provided with an aperture for a shade roller trunnion, 125 said arm being provided at its elbow with a curved camming surface adapted for engagement and cooperation with the upper edge of an associated lower window sash to force said supporting arm to swing upwardly when the associated sashes are moved by one another.

EDWARD JONAS.
